UNITED STATES PATENT OFFICE.

JOHN W. SEAVER AND SAMUEL T. WELLMAN, OF CLEVELAND, OHIO,
ASSIGNORS TO THE WELLMAN-SEAVER ENGINEERING COMPANY,
OF SAME PLACE.

CRANE.

SPECIFICATION forming part of Letters Patent No. 655,522, dated August 7, 1900.

Application filed July 21, 1898. Serial No. 686,522. (No model.)

To all whom it may concern:

Be it known that we, JOHN W. SEAVER and SAMUEL T. WELLMAN, citizens of the United States, and residents of Cleveland, Ohio, have 5 invented certain Improvements in Cranes, of which the following is a specification.

Our invention consists of a crane intended especially for use on piers or wharves, although applicable for other purposes where a crane 10 having a projecting boom is required, the object of our invention being to so construct the crane that it will be of simple construction, quick acting, of large capacity, and will have a wide range of action both on the pier and 15 on a vessel docked alongside said pier.

In the accompanying drawings, Figure 1 is a side view of a crane constructed in accordance with our invention and showing the boom drawn in. Fig. 2 is a similar view of 20 the crane, showing the boom run out. Fig. 3 is an end view of the crane. Figs. 4 and 5 are side views of modified forms of crane embodying the invention, and Fig. 6 is an end view of the crane shown in Fig. 5.

25 Fitting-out piers, such as form part of a modern ship-yard plant, are usually equipped either with stationary shears or with derricks having revolving jibs; but both of these structures have a limited range of action and 30 are attended with more or less inconvenience in operation, and the floating derricks which are sometimes used are also troublesome, besides being expensive. The crane which we have devised covers a large field of action 35 upon the wharf or pier and may, if desired, cover the entire area of the same, and it enables a load to be quickly and accurately placed in any desired position on board a ship or other craft which may be lying at the 40 wharf or affords equal facility for the transfer of loads from the craft to the wharf.

The invention consists of a traveling crane or gantry composed of a girder 1, supported at each end by a frame or legs 2 and carrying a sliding boom 3. The girder 1 is preferably composed of opposite channel bars or beams, which may be suitably connected or braced at the rear ends, but provide a free space between the front ends for the passage 45 of the hoisting rope or chain, and the boom 3

may consist of opposite beams or bars connected at each end and provided with one or more trolleys 4, each having suitable hoisting mechanism. The end frames or legs 2 of the crane are mounted upon trucks which 55 have wheels running upon rails on the wharf or pier, and the crane may be caused to travel up and down said wharf by means of power-driven mechanism of any available character. The sliding boom is provided with suitable 60 roller-bearings on the crane-girder, so that it can be run out beyond the edge of the wharf for as much of its length as desired, a sufficient part of the length of the boom being always retained in board to steady and hold it. 65

In the construction shown in Figs. 1, 2, and 3 the boom runs upon rollers 5 at the front end of the girder 1 and carries at its inner end rollers 6 and 7, running, respectively, upon the upper and lower flanges of the beams 70 constituting said girder, so as to prevent tipping or tilting of the boom when the same is run out.

Mechanism of any desired character having as its motive power electricity, air, water, 75 or steam may be used for imparting movement to the boom 3, and like mechanism may be used for traversing the trolleys 4 on the boom or for operating the hoisting mechanism of said trolleys, these details forming no 80 essential part of our present invention and being modified to suit the requirements of any particular case.

The end frames or legs, which support the girder 1, are so arranged that the boom 3, with 85 its trolleys and load, can pass between said legs, and for this purpose the legs may be strengthened or braced over the top of the girder 1, as shown at 8 in Fig. 3, and spread at their lower ends to such an extent as to 90 afford a proper base for the crane. At or near the bottom the legs may also be connected together by means of a tie-beam—such, for instance, as shown at 9 in Fig. 3—or the strength and construction of the legs may be 95 such that they will maintain themselves properly without the use of this lower tie-beam, so that the load will not have to be lifted over the same as the boom is run in or out.

We prefer to use on the boom 3 two trol- 100

leys, the outer one being designed for light loads and the inner one for heavy loads, and the heavy trolley, with or without a load, may, if desired, be used as a counterweight for the boom by running it into or toward the inner end of the same when the other trolley is run out to or toward the outer end of the boom; or, in order to counterweight and prevent tipping of the main crane structure when the boom is extended and carries a load at the outboard end, the inner trolley may, as shown by dotted lines in Fig. 2, be run onto a shelf or platform 10, secured to the inner frame or legs 2, weight being suspended from the trolley or the weight being otherwise applied to the inner frame or legs, as desired. In place of a moving trolley or trolleys the boom may have one or more sets of stationary lifting-gear, as desired, the movable trolleys being, however, always preferred.

It will be evident that with a crane constructed in accordance with our invention a load can be lifted from any place on the wharf within the field of the crane, and the crane can then be traversed along the wharf until it reaches a position directly abreast that point on the ship at which it is desired to place the load, whereupon the boom 3 can be run out over the ship and the trolley moved along on the boom until the load is in the exact position in which it is desired to place it, the load being handled without obstruction by the masts of the ship or other obstacles and the crane readily accommodating itself to the exigencies of any service which may be required.

In the modified form of crane shown in Fig. 4 brackets 11 on the girder 1 carry rollers 12 for bearing upon the top of the boom and 40 steadyng the same, while in Figs. 5 and 6

we have shown a telescopic construction, in which the boom 3 runs between the beams of the girder 1 and has at the inner end rollers 13 and 14, bearing, respectively, against the upper and lower flanges of said beams, the 45 trolley or trolleys running inside of the boom.

Other methods of constructing and combining the boom and girder of the crane within the scope of our invention will readily suggest themselves to those skilled in the art to 50 which said invention appertains.

Hence, without limiting ourselves to the details of construction which we have shown and described, we claim and desire to secure by Letters Patent—

1. A crane consisting of a girder, traveling end frames or legs supporting said girder and laterally braced or connected above the same, and a sliding boom mounted on said girder, substantially as specified.

2. A traveling crane having a girder and a boom mounted so as to slide thereon, said boom having a pair of independently-moving trolleys whereby one of said trolleys may be used as a counterweight when the other is 65 lifting, substantially as specified.

3. A traveling crane having a girder with boom mounted thereon so as to be free to slide, a pair of independently-movable trolleys for said boom, and a fixed shelf or platform on the crane structure for the reception of the inner trolley, substantially as specified.

In testimony whereof we have signed our names to this specification in the presence of two subscribing witnesses.

JOHN W. SEAVER.

SAMUEL T. WELLMAN.
